REFRIGERATING APPARATUS

Donald H. Reeves, Dayton, Ohio, assignor to General Motors Corporation, Dayton, Ohio, a corporation of Delaware

Application September 25, 1940, Serial No. 358,331

10 Claims. (Cl. 312—156)

This invention relates to refrigerating apparatus and particularly to refrigerator cabinets.

An object of my invention is to improve the appearance of the interior of a household refrigerator cabinet by providing an improved method of supporting shelves within the food storage chamber of the cabinet.

Another object of my invention is to improve the appearance of the interior of a refrigerator cabinet by incorporating mounting devices, for shelves adapted to be positioned in the food storage chamber thereof, in the chamber throat structure or in the wall construction of the access door opening of the cabinet in such a manner that these devices form the sole support for such shelves and permit the chamber walls to be smooth and unobstructed.

A further object of my invention is to incorporate shelf supporting devices in the food storage chamber throat structure or in the wall construction of the access door opening of a refrigerator cabinet, in such a manner that the devices at the front of the chamber form the sole supporting means for slidably receiving a shelf and supporting the same within the chamber or in any one of a plurality of horizontally moved or slidable positions outwardly of the chamber.

In carrying out the foregoing objects, it is a still further object of my invention to provide, in the food storage chamber throat structure of a refrigerator cabinet, shelf supporting devices that are vertically adjustable to accommodate a shelf in any one of a plurality of elevated positions thereof within the chamber and to conceal the mounting portion of the devices by the wall or breaker strip located at the chamber access opening.

Further objects and advantages of the present invention will be apparent from the following description, reference being had to the accompanying drawings, wherein a preferred form of the present invention is clearly shown.

In the drawings:

Fig. 1 is a front view of a refrigerator cabinet showing the food storage chamber access door in open position and showing shelves mounted in the chamber in accordance with the present invention;

Fig. 2 is an enlarged fragmentary horizontal sectional view taken on the line 2—2 of Fig. 1, showing the support of a shelf from one side of the wall structure of the food storage chamber access opening;

Fig. 3 is a vertical sectional view taken on the line 3—3 of Fig. 2, showing the adjustable mount-

ing of a shelf support at the food storage chamber access opening;

Fig. 4 is a side view of the shelf support shown in Fig. 2 and taken on the line 4—4 of Fig. 3, illustrating its mounting upon the cabinet;

Fig. 5 is a view similar to Fig. 2 showing a modified shelf support at one side of the food storage chamber access opening;

Fig. 6 is a vertical sectional view taken on the line 6—6 of Fig. 5 showing the mounting of the modified shelf support to the cabinet; and

Fig. 7 is a side view of the modified shelf support shown in Fig. 5 and is taken on the line 7—7 of Fig. 6.

15 Referring to the drawings, for illustrating my invention, I show in Fig. 1 thereof, a refrigerating apparatus comprising a refrigerator cabinet 10 having outer metal walls or a wall member 11 and an inner metal liner member 12 providing walls of a food storage chamber 14 within the cabinet. Any suitable or desirable insulating material 16 (see Fig. 2) may be located between the outer cabinet walls 11 and liner 12 to insulate the storage chamber. A cooling unit or evaporator 17 of a closed refrigerant circulating system may be disposed within the upper part of chamber 14. The evaporator 17 is adapted to be connected with a refrigerant liquefying unit (not shown) usually mounted in a machine compartment provided in cabinet 10 below the chamber 14. Refrigerant evaporated in evaporator 17 chills air within chamber 14 and causes circulation of air within the chamber to cool food stored therein. The chamber 14 is divided into a plurality of superimposed compartments or food storage spaces by vertically spaced apart horizontally disposed shelves 18. The cabinet outer metal wall member 11 and the metal liner member 12 are each provided with an aperture which register with one another to provide the chamber 14 with an access opening at the front of cabinet 10. A door 19 pivotally mounted upon cabinet 10 normally closes the food storage chamber access opening. Since the present invention is directed to improving the appearance of the interior of a food storage chamber of a refrigerator cabinet, I propose the support of shelves within the chamber solely from devices mounted exteriorly of the chamber. For example, I contemplate the incorporation of shelf supporting devices in the throat structure or in the wall construction of the access door opening of the food storage chamber to thereby eliminate shelf pegs projecting inwardly from walls of the chamber. Preferably the shelves are to be supported as

described so as to permit sliding same into and out of the food storage chamber. An inturned edge 21 of the aperture in the outer cabinet wall member 11 is spaced from the edge of the aperture in the metal liner member 12 of chamber 14 at the throat or access opening of the chamber to break the metal-to-metal contact therebetween for preventing the transfer of heat into the chamber from exteriorly thereof (see Fig. 2). A portion of the liner 12 inwardly of its edge, is formed outwardly away from or substantially at right angles to the chamber vertical side walls, as at 22, and is reversely bent, as at 23. This reversely bent portion of liner 12 is further bent as at 24, to provide a flange-like mounting edge portion 26. The vertical edge portion 26 of liner member 12, on each side of the chamber access opening, has a means in the form of a vertically elongated rigid metal member secured thereto by a plurality of spaced apart screws 29 which pass through the liner mounting edge portion 26 and have a nut 31 thereupon. A mould element or trim strip 33, of any suitable and preferably hard insulating material, overlaps the metal member 28 and the edge 21 of cabinet wall member 11 to close the gap between the apertures in members 11 and 12 at the access opening of cabinet 10. The mould element 33 forms a wall or walls for the chamber throat or access door opening and provides an insulated wall structure which prevents heat transference between the inside and outside of chamber 14. A plurality of vertically spaced apart screws 34 extend through mould element 33 along one edge thereof and are threaded into the edge portion 21 of the outer cabinet wall 11. A plurality of screws 36 spaced from the inner edge of mould element 33 extend therethrough and through suitable openings provided in metal member 28 and are threaded into mounting edge portion 26 of the liner member 12. The screws 34 and 36 securely hold the mould element or trim strip 33 in position on the cabinet walls and space the edge portion of the apertures in members 11 and 12 a predetermined distance apart. Each of the metal members 28, on opposite sides of the chamber access opening, is securely fastened to the cabinet 10 in back of the mould element 33 by being secured to liner 12 by the bolts 29-31. These metal members 28 each have a portion adjacent one edge bent to extend parallel with the extension of the chamber side wall formed by liner 12. Each member 28 has a plurality of vertically spaced apart elongated cut-away portions 41 provided in the one edge thereof, which edge abuts the outwardly formed portion 22 of liner 12. The abutment of this edge portion of member 28, intermediate the cut-away portions 41, thus causes the outwardly formed portion 22 of liner 12 to cooperate with the cut-away portions 41 of member 28 to form walls of a plurality of vertically spaced apart holes 42 along the sides of the chamber door opening (see Figs. 3 and 4) for a purpose to be presently described.

A rigid metal element, generally represented by the reference character 45, is disposed in the space between the liner 12 and the inner edge of mould element 33, at each side of the chamber access opening. Each rigid element 45 comprises a vertically disposed part 46 extending parallel with the outwardly formed part 22 of liner 12 and which is substantially concealed by the mould element 33. This part 46 of element 45 bears against the portion 22 of liner 12 and

divides the force applied to the liner by the weight of shelf 18, between the front corner of chamber 14 and the edge portion 26 of liner 12 through the element mounting member 28. The edge of part 46 of element 45 is cut away in two places, as at 47 and 48, to provide hook-like projections 49 and 51 (see Fig. 3). Walls of the cut-away portions 47 and 48 bear against the side of member 28 and the hook-like projections 49 and 51 extend through the holes 42 and removably hook over the bottom wall of the cut-away portions 41, of member 28. The hook-like projections are vertically spaced apart a sufficient distance to extend through alternate holes of the equally spaced apart holes 42. This removable attachment of the part 46 of elements 45 to the members 28, securely holds the elements 45 upon the cabinet along the sides of the chamber access opening in back of the mould element 33. Each rigid metal element 45 also comprises another part 53 which extends away from the part 46 thereof horizontally into chamber 14 along a side wall of the chamber. This other part 53 of the elements 45, includes a vertical wall portion 54 and horizontally disposed upper and lower wall portions 56 and 57 respectively, forming a horizontally elongated track-like portion adapted to slidably receive a shelf. The upper wall portion 56 of part 53 is provided with spaced apart depressions 58 and the bottom wall portion 57 thereof is provided with spaced apart raised portions 59. The purpose of the depressions 58 and raised portions 59, in the track-like part 53 of elements 45, is to provide points of contact with a shelf, in order to reduce friction of engagement of the shelf with the track-like part of elements 45. Each shelf 18 within the food storage chamber 14 of the refrigerator cabinet 10, comprises front and back rails 62 and side rails 63 and a food supporting surface formed by a plurality of wires 64 extending between and secured to the front and back rails thereof. The side rails 63 of shelf 18 are disposed in the track-like device or portion of the part 53 of elements 45, mounted on opposite sides of the access opening of chamber 14, to thereby slidably mount the shelf 18 within the chamber. It will be noted that when the shelf is supported by the elements 45, its side rails 63 are engaged only by the depressions 58 and the raised portions 59 of the track device. The horizontally elongated mounting of shelf 18 within chamber 14 forms the sole support for the shelf in any one of a plurality of slidable or adjusted positions relative to the interior of chamber 14. The use of additional shelf supporting means at the rear of chamber 14 is thus eliminated and the shelf is supported solely by mounting elements or devices incorporated in or associated with the chamber throat structure or the access door opening construction thereof. The shelf supports or mounting devices 45 may be removed from one secured position upon the cabinet to another secured position thereon, so as to accommodate vertical adjustment of a shelf 18. Should it be desired to elevate or lower the shelf 18, the supports or devices 45 are released from their attachment to the cabinet by elevating the same so that the hook-like portions 49 and 51, formed on the part 46 thereof, may be pulled outwardly of the holes 42. After opposed supports or mounting devices 45 have been removed from the members 28, they may again be attached to the cabinet at any desired aligned

points of elevation by pushing the hook-like portions 49 and 51 through other of the holes 42 and then forcing them downwardly so that the hooks 49 and 51 fit over and interlock with the bottom wall of the cut-out portions 41 of members 28. The space between the inner edge of mould element 33 and liner 12 permits the devices 45 to be moved therein along the sides of the chamber.

In Figs. 5 to 7 inclusive, of the drawings, I have shown a modified form of my invention wherein the shelf supports or mounting devices are removably attached directly to the food storage chamber liner and exteriorly of the chamber proper to thus eliminate the provision of the mounting member along the edge of the liner, as previously described. In Fig. 5, of the drawings, the liner 12a, of the food storage chamber 14a, is formed outwardly away from or substantially at right angles to the chamber vertical side wall, as at 22a, and is reversely bent, as at 23a. This portion of liner 12a adjacent its edge, is also bent as at 24a, to provide a flange-like mounting at edge portion 26a. A mould element or trim strip 33a, similar to the element 33, overlaps the edges of the metal members 11a and 12a, and bridges the gap therebetween, at the access opening of the cabinet and this element 33a forms a wall for the throat or access opening of chamber 14a. The mould element 33a abuts, and is directly secured to the mounting flange portion 26a of liner 12a by a plurality of vertically spaced apart screws 36a, and is secured to the inturned portion 21a of metal member 11a by screws 34a. In this modified form of the invention, I provide a plurality of vertically aligned and elongated openings 71 (see Figs. 6 and 7), in the reversely bent portion 23a of liner 12a, to form mountings substantially concealed from view at the front of chamber 14a, by the wall element 33a, for the reception of a shelf support element or device 45a. The part 53a of elements or devices 45a, in this form of my invention, is the same as that described relative to the part 53 of the shelf supporting elements or devices 45. The part 46a, of elements or devices 45a, are of somewhat different form than the form of part 46, of elements 45, in that this part 46a comprises a single hook-like projection 72 and a vertically extending short laterally disposed portion 73 (see Fig. 6). Part 46a, of each element adapted to be disposed on opposite sides of the access opening of chamber 14a, extends parallel with the outwardly formed portion 22a, of liner 12a, and is bent as at 74 (see Fig. 5). The part 46a, of elements 45a, disposed between the mould element 33a and the portion 22a of liner 12a, bears against the liner and thereby divides the force applied to the liner by the weight of shelf 18a, between the front corner of chamber 14a and the reversely bent portion 23a of the liner. The hook-like projection 72, extends through one of the openings 71, in the part 23a of liner 12a, and hooks over the bottom wall of the opening to engage one surface of the liner part 23a and the portion 73, of the element 45a, bears against the other surface of the reversely bent liner part 23a. The rigid elements 45a are thereby firmly held in a shelf supporting position and are removably mounted directly upon the liner 12a. These shelf supports or mounting devices 45a may also be removed from one secured position thereof upon the cabinet to another secured position thereon, to accommodate vertical adjustment of a shelf 18a. Should it be desired to change the elevation of the shelf

18a, the elements 45a, on each side of the chamber access opening are raised, to permit the hook-like part 72 thereof to clear the bottom wall of the opening 71, and pulled outwardly away from the portion 23a, of the liner 12a, to thereby free the same from the liner. The elements 45a may then be moved upwardly or downwardly in the space between liner 12a and the mould element 33a, for insertion of the hook-like part 72 thereof into any one of other of the openings 71, to alter the elevation of attachment of elements 45a to the cabinet, for the purpose of accommodating any desired vertical adjustment of a shelf 18a within the chamber 14a.

15 It is, of course, to be understood that in either form of structure herein disclosed, the shelf is first removed from its mounting devices prior to moving the devices vertically along the side walls of the food storage chamber. The modified form 20 of shelf supports or mountings, shown in Figs. 5 to 7 inclusive, are like the supports or mountings shown in Figs. 1 to 4 inclusive, in respect to the feature of the supports at the front of the chamber, forming the sole support means for a shelf 25 disposed within the food storage chamber of the cabinet.

From the foregoing, it will be apparent that I have provided an improved means for supporting shelves within a food storage chamber of a refrigerator cabinet, and have made provisions for adjusting the elevation of a shelf in my improved supporting means. My improved shelf supporting means forms the sole support of a shelf within the food storage chamber from a point exteriorly of the chamber and in the chamber throat structure or access opening wall construction. By my invention, I eliminate the attachment to and projection from walls of the chamber of pegs or other shelf supports. The sole support of a shelf from a support incorporated in the food chamber access opening wall structure as disclosed is constructed to permit sliding of shelves outwardly of the chamber to facilitate removal of food placed thereon for storage in the chamber. The mounting of my improved shelf supports, in the manner disclosed, is substantially concealed from view at the front of the food storage chamber and this concealment improves the appearance of the interior of the chamber.

50 While the form of embodiment of the invention as herein disclosed, constitutes a preferred form, it is to be understood that other forms might be adopted, all coming within the scope of 55 the claims which follow.

What is claimed is as follows:

1. In combination, a refrigerator cabinet provided with a liner defining a plurality of walls of a food storage chamber therein, said cabinet having an aperture therein forming an access opening for said chamber, a mold element forming a wall for said chamber access opening, a door for normally closing said opening, shelf supporting means having a portion thereof disposed between said liner and said mold element at each side of said chamber access opening, each of said means including a part secured to said cabinet exteriorly of said chamber and concealed by said mold element, and each of said means including another part extending a substantial distance into said chamber along a side wall thereof and being constructed and arranged to form the sole supporting means for a shelf adapted to be positioned within said chamber.

2. In combination, a refrigerator cabinet pro-

vided with a liner defining a plurality of walls of a food storage chamber therein, said cabinet having an aperture therein forming an access opening for said chamber, a mold element forming a wall for said chamber access opening, a door for normally closing said opening, shelf supporting means having a portion thereof disposed between said liner and said mold element at each side of said chamber access opening, each of said means including a part secured to said cabinet exteriorly of said chamber and concealed by said mold element, each of said means including another part extending a substantial distance into said chamber along a side wall thereof, and said other part of said means being constructed and arranged to provide a track-like device for slidably supporting a shelf within said chamber.

3. In combination, a refrigerator cabinet provided with a liner defining a plurality of walls of a food storage chamber therein, said cabinet having an aperture therein forming an access opening for said chamber, a mold element forming a wall for said chamber access opening, a door for normally closing said opening, a rigid shelf supporting element having a portion thereof disposed between said liner and said mold element at each side of said chamber access opening, each of said rigid elements including a part extending in back of said mold element and adapted to be detachably mounted upon said cabinet, means concealed by said mold element for receiving said mounting part of said rigid elements, each of said rigid elements also including another part extending away from said mold element a substantial distance into said chamber along a side wall thereof to form the sole supporting means for a shelf adapted to be positioned within said chamber, and said receiving means being so constructed and arranged as to permit reception of said mounting part of said elements at a plurality of vertically spaced apart points along the sides of said chamber access opening.

4. In combination, a refrigerator cabinet provided with a liner defining a plurality of walls of a food storage chamber therein, said cabinet having an aperture therein forming an access opening for said chamber, a mold element forming a wall for said chamber access opening, a door for normally closing said opening, a portion of said liner adjacent the chamber access opening and along the sides thereof being formed outwardly, said outwardly formed portion of said liner being reversely bent and having a flanged edge part extending therefrom to provide a mounting for said mold element, said reversely bent portion of said liner being provided with a plurality of vertically spaced apart openings therein along opposed sides of said chamber access opening, a rigid shelf supporting element having a portion thereof disposed between said liner and said mold element at each side of said chamber access opening, each of said rigid elements including a part disposed in back of said mold element and detachably mounted in one of the openings in said reversely bent portion of said liner, each of said rigid elements also including another part extending away from said mold element a substantial distance into said chamber along a side wall thereof to form the sole supporting means for a shelf adapted to be positioned within said chamber, and said openings in said reversely bent portion of said liner being arranged to permit the mounting of said rigid elements therein at any one of a plurality

of vertically spaced apart points along the sides of said chamber access opening.

5. In combination, a refrigerator cabinet provided with a liner defining a plurality of walls of a food storage chamber therein, said cabinet having an aperture therein forming an access opening for said chamber, a mold element forming a wall for said chamber access opening, a door for normally closing said opening, a portion of said liner adjacent the chamber access opening and along the sides thereof being formed outwardly, said outwardly formed portion of said liner being reversely bent and having a flanged edge part extending therefrom to provide a mounting for said mold element, said reversely bent portion of said liner having an opening therein at opposed sides of said chamber access opening, a rigid shelf supporting element having a portion thereof disposed between said liner and said mold element at each side of said chamber access opening, each of said rigid elements including a part disposed in back of said mold element and mounted in the opening provided in said reversely bent portion of said liner, and each of said rigid elements also including another part extending away from said mold element a substantial distance into said chamber along a side wall thereof to form the sole supporting means for a shelf adapted to be positioned within said chamber.

6. In combination, a refrigerator cabinet provided with a liner defining a plurality of walls of a food storage chamber therein, said cabinet having an aperture therein forming an access opening for said chamber, a mold element forming a wall for said chamber access opening, a door for normally closing said opening, a portion of said liner adjacent the chamber access opening and along the sides thereof being formed outwardly, said outwardly formed portion of said liner being reversely bent and having a flanged edge part extending therefrom to provide a mounting for said mold element, said reversely bent portion of said liner having an opening therein at opposed sides of said chamber access opening, a rigid shelf supporting element having a portion thereof disposed between said liner and said mold element at each side of said chamber access opening, each of said rigid elements including a part disposed in back of said mold element and mounted in the opening provided in said reversely bent portion of said liner, each of said rigid elements also including another part extending away from said mold element a substantial distance into said chamber along a side wall thereof, and said other part of said rigid elements being constructed and arranged to provide a track-like device for slidably supporting a shelf within said chamber.

7. In combination, a refrigerator cabinet provided with a metal outer wall member and an inner metal liner member defining walls of a food storage chamber within said cabinet, each of said members having an aperture therein registering with one another to provide an access opening for said chamber at the front of said cabinet, a door for normally closing said access opening, the edges of said members being spaced apart at said access opening to break the metal-to-metal contact therebetween, a mold element forming a wall for said access opening and concealing the edges of said members, a portion of said metal liner adjacent the edge thereof along opposed sides of said access opening being formed outwardly, shelf supporting means having a por-

tion thereof disposed between the edge of said mold element and said liner at each side of said chamber access opening, each of said means having a part thereof extending in a direction parallel to the extension of said outwardly formed portion of said liner and secured to said cabinet in back of said mold element whereby the mold element conceals same, each of said means also having another part extending a substantial distance into said chambers along a side wall thereof, and said other part of said means being so constructed and arranged as to form the sole support for a shelf adapted to be positioned in said chamber.

8. In combination, a refrigerator cabinet provided with a metal outer wall member and an inner metal liner member defining walls of a food storage chamber within said cabinet, each of said members having an aperture therein registering with one another to provide an access opening for said chamber at the front of said cabinet, a door for normally closing said access opening, the edges of said members being spaced apart at said access opening to break the metal-to-metal contact therebetween, a mold element forming a wall for said access opening and concealing the edges of said members, a portion of said metal liner adjacent the edge thereof along opposed sides of said access opening being formed outwardly, shelf supporting means having a portion thereof disposed between the edge of said mold element and said liner at each side of said chamber access opening, each of said means having a part thereof extending in a direction parallel to the extension of said outwardly formed portion of said liner and secured to said cabinet in back of said mold element whereby the mold element conceals same, each of said means also having another part extending a substantial distance into said chamber along a side wall thereof, and said other part of said means being so constructed and arranged as to form the sole support for a shelf adapted to be positioned in said chamber.

9. In combination, a refrigerator cabinet provided with a metal outer wall member and an inner metal liner member defining walls of a food storage chamber within said cabinet, each of said members having an aperture therein registering with one another to provide an access opening for said chamber at the front of said cabinet, a door for normally closing said access opening, the edges of said members being spaced apart at said access opening to break the metal-to-metal contact therebetween, a mold element forming a wall for said access opening and concealing the edges of said members, a portion of said metal liner adjacent the edge thereof along opposed sides of said access opening being formed outwardly, said outwardly formed portion of said liner being reversely bent and having a flanged edge part extending therefrom to provide a mounting for said mold element, means secured

to said flanged edge part of said liner in back of said mold element and provided with a plurality of vertically spaced apart openings therein for receiving a part of a shelf support, a rigid shelf supporting element having a portion thereof disposed between the edge of said mold element and said liner at each side of the chamber access opening, each of said elements having a part extending in a direction parallel to the extension of said outwardly formed portion of said liner mounted within certain of said openings in said means and concealed by said mold element, and each of said rigid elements also having another part extending away from said mold element a substantial distance into said chamber along a side wall thereof to form the sole support for a shelf adapted to be positioned in said chamber.

10. In combination, a refrigerator cabinet provided with a metal outer wall member and an inner metal liner member defining walls of a food storage chamber within said cabinet, each of said members having an aperture therein registering with one another to provide an access opening for said chamber at the front of said cabinet, a door for normally closing said access opening, the edges of said members being spaced apart at said access opening to break the metal-to-metal contact therebetween, a mold element forming a wall for said access opening and concealing the edges of said members, a portion of said metal liner adjacent the edge thereof along opposed sides of said access opening being formed outwardly, said outwardly formed portion of said liner being reversely bent and having a flanged edge part extending therefrom to provide a mounting for said mold element, means secured to said flanged edge part of said liner in back of said mold element and provided with a plurality of vertically spaced apart openings therein for receiving a part of a shelf support, a rigid shelf supporting element having a portion thereof disposed between the edge of said mold element and said liner at each side of the chamber access opening, each of said elements having a part extending in a direction parallel to the extension of said outwardly formed portion of said liner detachably mounted within certain of said openings in said means and concealed by said mold element, each of said rigid elements also having another part extending away from said mold element a substantial distance into said chamber along a side wall thereof, said other part of said rigid elements being so constructed and arranged as to provide a track-like device for slidably supporting a shelf within said chamber, and said openings in said means being arranged to permit the mounting of said rigid elements in other of said openings than said certain openings to permit adjustment of said rigid elements vertically along the sides of said chamber access opening.

DONALD H. REEVES.
